KARL CHRISTEL, OF TAUCHA, GERMANY

MACHINE FOR CLEANING THE MATRICES FOR TYPE SETTING AND CASTING MACHINES

Application filed February 26, 1927, Serial No. 171,320, and in Germany February 27, 1926.

Heretofore, machines and apparatus have become known, by which the cleaning of the brass matrices for type setting and casting machines takes place in a more or less advantageous manner. It is also known that such matrices are very sensitive and that high losses result from a bad treatment and cleaning of the same due to the requirement of a repeated renewal thereof. On the other hand, a cleaning by hand is very time-wasting and thereby disturbs the normal working of the type setting and casting machines.

The hitherto known cleaning machines possess the drawback that their construction is very cumbersome and sensitive and that they require a particularly careful attendance, treatment and cleaning, whereby the costs of manufacture and working of such machines are rather high.

The present invention provides an improved cleaning machine of simple construction, through the cleaning contrivances of which the matrices to be cleaned can be automatically passed as often as desired; importance being however attached to the fact that the cleaning and polishing of the matrices is attained by passing the same twice through the machine, the matrices being cleaned at one broad side during the first passage and at the other broad side during the second passage through the machine, and correspondingly at its longitudinal edges.

The accompanying drawings illustrate a preferred constructional form of the improved machine:

Fig. 1 is a side view thereof, partly in section on the line 1—1 of Fig. 2;

Fig. 1^a is a cross section on the line 1^a—1^a of Fig. 1.

Fig. 2 is a horizontal section therethrough on the line 2—2 of Fig. 1;

Figs. 3 and 4 are respectively a plan view and a side view of a matrix to be cleaned.

Figs. 5 and 6 are respectively a side view and a plan view of part of a detail, and

Figs. 7 and 8 are respectively a side view and a plan view of another detail, of the machine, said matrix and two details being shown on a larger scale than in Figs. 1 and 2;

Fig. 9 is a vertical cross-section on the line 9—9 of Fig. 2;

Fig. 10 is a section on the line 10—10 of Fig. 11, which is a section through part of the machine on a larger scale on the line 1—1 of Figs. 9, 10 or 2;

Figs. 12 and 13 are respectively a side view and an end view of a detail, and

Figs. 14 and 15 are respectively a side view and an end view of another detail, of the machine shown in Fig. 11;

Figs. 16 and 17 are side views, partly in section on the line 1—1 of Figs. 9 or 2, on a larger scale of part of the machine, in two different positions of the movable parts thereof;

Fig. 18 is a horizontal section on the line 18—18 of Fig. 17; and

Fig. 19 is a side view of a machine similar, and with certain parts thereof in different position, to that shown in Fig. 1.

To create a continuous automatic circulation of the matrices 5 (Figs. 3 and 4) through the machine, that is, for automatically returning the matrices to the feeding channel, the centrifugal force of the disc *h* designed for cleaning the broad sides of the matrices and rotating in the flying direction of the latter, is used. Upon the matrices being freed from the locking rails *g*, they are caused to participate in the rotary movement of the disc, from which they are lifted at an appropriate moment by the guiding rails *v* and projected, due to the centrifugal force imparted to them by the disc *h*, through the gabled return channel *n*, *o* into the vertical collecting channel *a* serving at the same time as feeding channel, for which purpose it is fitted with a hinged or detachable cover *a*¹. The guiding rails *v* are fixed to lateral guide-
90 plates of the machine frame and located at such a distance from one another that the disc *h* can just rotate between them. The upper ends of said guiding rails *v* adjoin the lower end of the flying channel *n*, *o* and their lower ends embrace part of the disc *h* (Figs. 1, 2 and 16).

It is of importance that the disc *h* consists of a plurality of layers of woven fabric for allowing the matrices to make sufficient

contact therewith for receiving therefrom the required centrifugal force. During their flying passage through the gabled return channel n , o , the matrices are turned about their longitudinal axis, so that during their next passage through the machine their opposite broad side and longitudinal edges are cleaned. Said upside-down turning of the matrices, after each passage through the 10 cleaning contrivances is effected by the downwardly directed branch o of the gabled return channel, which to this end consists of a brass pipe of oval cross-section which is twisted for 180° on its whole length about its longitudinal axis. That part of the upwardly directed branch n of the gabled return channel adjacent to the rotary cleaning disc h is open at its lower end so that matrices, which do not attain the vertex x of the gabled return channel due to unsatisfactory rotary 20 speed of the cleaning disc h and therefore fall back, can fall out of the gabled return channel after having slipped down the inclined plane formed by the latter.

25 The principal cleaning of the broad sides of the matrices takes place underneath the cleaning disc h , and for thoroughly cleaning the same they must be locked for some time beneath the quickly rotating disc. This is attained by the locking rails g (Fig. 16) consisting of two parallel narrow rails of tempered steel, which are riveted to one another at the distance of the breadth of a matrix and adapted to turn on a fulcrum 30 i . Between said rails g the disc h is rotatably mounted. The left-hand end of said rails is inclined, while their right-hand end is hook-shaped by the provision of a recess 35 6 in the middle of each rail. To this end of the rails, besides, two draw-springs r are attached which tend to pull the hook continuously into its position of rest.

40 The locking and unlocking of the matrices by the locking rails g takes place as follows: 45 The matrix supplied by the conveyor chain b lifts the locking rails g and is pushed by the tappets c of the chain onto the springy bridge f and thus to the cleaning disc h . At this moment the locking rails g due to their 50 lower recessed portions 6 slip off from the tappets and are pulled by the draw-springs r into their position of rest. As soon as the matrix has arrived at the disc h , it is caught and liable to be driven along by said disc. 55 To prevent this, the matrix is somewhat braked by a spring 1 , so that the hook-shaped locking rails engage between the ears of the matrix and can lock the same during the 60 cleaning process. If, then, the following chain tappet arrives with another matrix and lifts the locking rails g , the preceding matrix hitherto locked by the hook is liberated and projected by the fly-disc h back into the feeding channel a . The succeeding matrix 65 having effected the disengagement of the pre-

ceding matrix, is then locked beneath the disc h , and so on. In case that the matrix lifting the locking rails is too thin for lifting the hook of the latter so far that the matrix locked thereunder is liberated, this is nevertheless reliably effected by the chain tappets c . 70

The supply of the matrices from the feeding channel a to the cleaning contrivance is effected in the following manner: The row 75 of superposed matrices in the feeding channel a bears below upon the horizontal member of an angle-piece s (Fig. 11), which is arranged on the left-hand side wall of the feeding channel and adapted to be adjusted in its position of height. Said angle-piece is so adjusted that the chain tappets c can always catch the lowermost matrix only, the stepped arresting-spring t preventing the 80 next superposed matrix from being advanced 85 with the lowermost matrix.

The tappets c are arranged on both sides of the conveyor chain, each two pairs of tappets belonging to each other and being connected, each by two screws forming at the 90 same time the chain bolts, with each other and with the chain (Figs. 5 and 6). The tappets lying in front, with reference to the direction of movement of the chain, serve for supporting the matrix only while the rear tappets 95 serve as a support therefor with a rear stop or abutment thereon. By this arrangement, the matrices are reliably advanced and offered to the cleaning action, first by a brush d mounted to yield somewhat in upward direction, then by a sweeper e , and finally by the 100 cleaning or polishing disc h serving at the same time as a fly-disc as explained.

The brush d is suspended from the pivoted beam 7 (Fig. 1) by means of two screws d^1 105 loosely passing through the latter and engaging in the back of the brush. Said screws carry coil springs d^2 between said beam and said brush back for resiliently mounting the brush within the path of the matrices in such a way that it comes in slight contact with the latter during their passage underneath the brush. To meet wear of the brush bristles, it is simply necessary to correspondingly unscrew the screws d^1 from the brush back. 110

The sweeper e (Figs. 7 and 8) comprises a rectangular thin blade-steel support clamped fast at its ends by means of two rails 8 and 9 screwed upon one another. Around said support and the upper rail 8 an endless cleaning 115 ribbon of suitable fabric is turnably placed and held in stretched position by means of a blade spring 11 fixed to the upper rail 8 . Said sweeper is suspended from the beam 7 (Figs. 1 and 19) and located between the brush d 120 and the disc h in such a way that it slightly touches the matrices during their passage underneath the sweeper, the resilient mounting of the ribbon 10 suiting different thicknesses 125 of matrices and its turnability around the 130

blade-steel support meeting a one-sided wear of the ribbon. Another square blade-steel support 12, suspended from the lower rail 9 and bearing from inside against the lower part of the ribbon ensures a uniform pressure of the latter upon the matrix to be swept. A superposed benzine container 2 attached to the beam 7 delivers benzine to the ribbon.

Brush *d* and sweeper *e* are each enclosed by an open-ended casing (see Fig. 19).

To allow an access to the path of the matrices and to the upper part of the endless conveyor chain *b* running therein, in the event of working disturbances, the brush and sweeper are so arranged on the pivoted beam 7 that they can be easily turned-up and again turned-down by one manipulation (Fig. 19). For the same purpose, also the quickly rotating cleaning disc *h*, by which as mentioned the principal cleaning of the broad sides of the matrices is attained, can be turned-up from its position of use, said disc being further adjustably mounted by means of screws *u* (Fig. 16) to meet the natural wear of the same. Furthermore, the downwardly directed branch *o* of the gabled return channel is easily detachable, while the latter can be easily opened at its curves *w*, *x* simply by turning its respective side walls upwards, the latter being hingedly arranged for this purpose (see dot-and-dash lines at *w* and *x* in Fig. 1).

To create a reliable transmission from the chain-wheel *y* (Fig. 16) to the rail *m* or respectively to the springy bridge *f* carried by the latter, and acted upon in its middle by a corrugated spring 13 and at its top by a blade spring 14 whereby the disc *h* is resiliently held down in its operative position; the angle-piece *s* (Fig. 11) has, at the left-hand side wall of the feeding channel *a*, a steel band *z* clamped thereto which extends to said springy bridge and is as broad as the chain *b* so that it lies between the chain tappets *c* and is kept in place by the latter. The further guiding of the matrix into the gabled return channel takes place by the lateral guide-plates *h* (Figs. 2 and 18), by the disc *h* and springy bridge *f* (Fig. 16). The latter is fixed on the rail *l*, which is adjustably fastened on the rail *m* to provide adjustment for wear of the disc *h*.

The upwardly inclined part *n* of the gabled return channel *n*, *o* is rectangular in cross-section and consists at its upper part of a flat-iron bar *p* and at its lower part of a U-shaped bar *q* fixed to the latter. A spring 15 (Fig. 16) is fixed to the lower end of the bar *p* to prevent a hard striking of the matrices against said bar, while a spring 16 at the lower end of the bar *q* ensures a safe transmission from the guiding rails *v* to the channel *n*.

The cleaning of the longitudinal edges of the matrices is effected by an emery strip 3 located on the inner side of the rear wall of

the casing enclosing the brush *d* directly behind the latter, and by the rotatable felt disc 4 (Fig. 9). The latter cleans the longitudinal edges of the matrix between the ears of the same by engaging in a recess in the rear wall of the feeding channel *a*. Both said contrivances 3 and 4 clean first one longitudinal edge of the matrix and, after the latter being turned upside down, the other longitudinal edge of the same.

What I claim, is:

1. A machine for cleaning matrices for type setting and casting machines, comprising a frame, a feeding channel at one end of said frame, means for cleaning the matrices including a rotatable disc at the other end of said frame, a conveyor to deliver matrices to said disc, to be cleaned, a gabled return channel for said matrices and guiding means to direct the matrices from the conveyor to the return channel, whereby said matrices upon being thrown by the centrifugal force of the rotating disc, will travel through the return channel to the feeding channel.

2. In a machine as specified in claim 1, means in the downwardly directed branch of said gabled return channel for turning the matrices upside down during their passage therethrough.

3. A machine as specified in claim 1, in which the upwardly directed branch of said gabled return channel is rectangular in cross-section.

4. In a machine as specified in claim 1, releasable locking means, including movably mounted rails having hooks thereon to catch said matrices and temporarily hold them below said cleaning disc to be cleaned.

5. In a machine as specified in claim 1, a brush and a sweeper arranged in front of said cleaning disc, all the three cleaning contrivances being pivotally supported and adapted to be turned-up for freeing the path of the matrices, and said sweeper consisting of a thin blade-steel frame and of an endless cleaning ribbon turnably placed and held in stretched position on the latter.

6. In a machine as specified in claim 1, an angle-piece of adjustable height on the lower end of said feeding channel serving as support for the lowermost matrix in said channel, a conveyor chain leading from said channel to said cleaning disc, tappets on both sides of said chain for advancing the lowermost matrix from said channel to said disc, and a stepped arresting spring for preventing the next matrix being advanced with the first matrix, said tappets being connected in pairs with each other and with the chain by means of screws serving at the same time as chain bolts.

7. In a machine as specified in claim 1, wherein said guiding means includes a springy bridge and guiding rails for con-

ducting the matrices projected by the centrifugal force of the cleaning disc into said gabled return channel.

8. In a machine as specified in claim 1,
means for preventing insufficiently projected
matrices from obturating the path through
said gabled return channel.

In testimony whereof I have hereunto set
my hand.

KARL CHRISTEL.
